Xan B. K. Green, New Paltz, and Harry Preble,
Jr., Cross River, N. Y., assignors to General
Slicing Machine Co., Inc., Walden, N. Y., a corporation of New York

Application July 7, 1953, Serial No. 25,822

Term of patent 14 years

(Cl. D55—1)

To all whom it may concern:

Be it known that we, Xan B. K. Green and Harry Preble, Jr., both citizens of the United States of America, residing, respectively, at the city of New Paltz, county of Ulster, and State of New York, and at the city of Cross River, county of Westchester, and State of New York, have jointly invented a new, original, and ornamental Design for an Electric Meat Grinder, of which the following is a specification, reference being had to the accompanying drawing, forming part thereof, wherein,

Fig. 1 is a perspective front view of an electric meat grinder showing our new design;

Fig. 2 is a perspective rear view thereof;

Fig. 3 is an elevational view of the side opposite those shown in Figs. 1 and 2, on a reduced scale.

We claim:

The ornamental design for an electric meat grinder, substantially as shown.
